ALKOXYALKYL IODOBENZOATES

Sydney Archer, Albany, N. Y., assignor to Sterling Drug Inc., Wilmington, Del., a corporation of Delaware

No Drawing. Application November 24, 1947,
Serial No. 787,853

8 Claims. (Cl. 260—476)

1

This invention relates to alkoxyalkyl monoiodobenzoates which have the formula

where Y is an alkylene bridge and R is alkyl, and wherein the total number of carbon atoms in the above formula is from 10 to 18. I prefer the compounds wherein Y has 2-3 carbon atoms and R has 1-6 carbon atoms, since these are most readily available from inexpensive starting materials.

My compounds are opaque to X-rays and therefore are valuable as contrast media in roentgenological examination of body cavities. They may be administered directly into the body cavities to be outlined. They are definite and stable chemical compounds in which the halogen is firmly attached to the phenyl radical.

I have found that these substances are of particular value in the roentgenological examination of the spinal cord and subarachnoid space, i. e., in that branch of radiography known as myelography. An ideal myelographic agent is one which is easily and rapidly administered and may be distributed readily and evenly to various parts of the cerebrospinal system, without, however, spreading into such thin layers that the radiopacity is lost. It should be eliminated readily, thereby avoiding having to remove it by aspiration, and be of low toxicity both locally and systemically.

Up to the present time, the various agents used for myelography include gases such as air and oxygen, thorium dioxide sols, iodized oils, and, more recently, a product consisting of a mixture of ethyl esters of isomeric iodophenylundecylic acids. Each of these agents has certain disadvantages. Gases are poor contrast media and difficult to administer properly, since their use requires replacement of part of the cerebrospinal fluid with gas, a procedure which may result in dangerous complications. Thorium dioxide sols lack the objectionable qualities of gases but have been found to cause untoward reactions, as well as introducing the possibility of eventual injury from residual radioactivity. Iodinated and brominated oils such as iodinated poppyseed oil, iodinated sesame oil, iodinated rapeseed oil and brominated olive oil, are effective and non-toxic contrast agents, but are largely unsatisfactory because of their high viscosity, and somewhat irritating properties. They must be injected

under pressure and after examination be withdrawn by aspiration, for otherwise they remain largely unabsorbed for a period of years, and cicatrix formation may result from prolonged contact with the tissues. Their high viscosity tends to cause separation of the oil into globules, rendering diagnosis difficult. The mixture of ethyl iodophenylundecylates is undoubtedly the best myelographic agent previously produced. It is less viscous than the iodinated glyceride oils and, therefore, is more easily introduced, withdrawn and absorbed. However, it is reported that at least a year is required for the complete absorption and elimination of as little as 0.5 to 1.0 cc. in man.

Although the possibility of using water-soluble radiopaque media as myelographic agents has been investigated, these compounds have been found unsatisfactory for a number of reasons. Diffusion is so rapid that the compound becomes diluted with spinal fluid, thereby losing its radiopacity unless a large quantity is injected, whereupon toxicity becomes an important factor since water-soluble substances are rapidly absorbed into the circulatory system.

The alkoxyalkyl monoiodobenzoates have many advantages over the above-described myelographic agents. For instance they are much more readily eliminated from the organism so that aspiration for removal is not required. They cause little or no irritation of membranes with which they come in contact. Experimental studies with several compounds within the scope of this invention have shown that appreciable amounts are completely eliminated from the cerebrospinal system of rabbits or cats within ten to twenty-five days with all but a trace being gone in a few days. Similar experiments in cats and dogs with ethyl iodophenylundecylate showed considerable material remaining in the spinal canal as long as eight months. Irritation tests in rabbits' eyes showed hyperemia of the conjunctiva from the latter compound more than is shown by the new compounds. The toxicities of my new compounds orally and intraperitoneally are low enough to permit the compounds to be safely used as myelographic agents. The esters of my invention have the advantage of being pure compounds instead of a mixture of isomers, and have a greater radiopacity due to a higher percentage of iodine (from 35 to 40% as compared with 30.5% for ethyl iodophenylundecylate).

My new compounds can be synthesized by the esterification of o-, m- or p-iodobenzoic acid by

one of the following methods: (1) the iodobenzoic acid and an alkoxyalkanol are combined directly in the presence of an acid catalyst; (2) said acid in the form of a reactive derivative, such as the acid chloride or anhydride, is caused to react with an alkoxyalkanol; or (3) a metallic salt of said acid is caused to react with an alkoxyalkyl halide. The following alkoxyalkanols are representative of the alcohols from which my new compounds are derived: 2-methoxyethanol, 2-ethoxyethanol, 2-propoxyethanol, 2-butoxyethanol, 3-methoxy-1-propanol, 3-ethoxy-1-propanol, 3-methoxy-2-propanol, 3-ethoxy-2-propanol, 4-methoxy-1-butanol, 5-methoxy-1-pentanol, and 2-(beta-ethylbutoxy)-ethanol. The corresponding halides, in which the hydroxyl groups are replaced by halogen, may be used if method (3) is employed.

The following examples will illustrate my invention more completely, but should not be construed as a limit to the scope of the invention, this being determined instead by the appended claims.

Example 1

2-methoxyethyl p-iodobenzoate.—A mixture of 30 g. of p-iodobenzoic acid and 110 cc. of thionyl chloride is refluxed for twenty hours on a steam bath. The excess thionyl chloride is removed at reduced pressure, 55 cc. of 2-methoxyethanol added, and the mixture is heated on a steam bath for one hour. The reaction mixture is then poured into ice-water, and the product is extracted with ether. The ether extracts are washed with water, 10% sodium carbonate solution, again with water, and dried over anhydrous sodium sulfate. After removal of volatile solvents, 2-methoxyethyl p-iodobenzoate distils at 144-146° C. (0.7 mm.); yield about 32 g. Viscosity, 13.8 centistokes.

Example 2

2-methoxyethyl m-iodobenzoate.—A mixture of 24 g. of m-iodobenzoic acid, 115 cc. of 2-methoxyethanol and 2 cc. of concentrated sulfuric acid is refluxed for sixteen hours. The reaction mixture is poured into ice-water, the product is extracted with ether, and the ether layer washed with water, 10% sodium carbonate solution, again with water, and dried over anhydrous sodium sulfate. After removal of volatile solvents, 2-methoxyethyl m-iodobenzoate distils at 142-145° C. (0.6 mm.); yield about 20 g. Viscosity 14.5 cs.

Example 3

2-ethoxyethyl p-iodobenzoate.—A mixture of 43.8 g. of p-iodobenzoyl chloride, 33.8 g. of 2-ethoxyethanol and 30 cc. of dry benzene is refluxed on a steam bath for three hours. The benzene is removed at reduced pressure and the reaction mixture poured into ice-water. The product is extracted with ether, washed with water, 10% sodium carbonate solution, again with water and then is dried over anhydrous sodium sulfate. After removal of volatile solvents, 2-ethoxyethyl p-iodobenzoate distils at 122-125° C. (0.04 mm.); yield about 42 g.

Example 4

2-ethoxyethyl m-iodobenzoate.—A mixture of 24 g. of m-iodobenzoic acid, 150 cc. of 2-ethoxyethanol and 2 cc. of concentrated sulfuric acid is caused to react and is worked up as in Example 2. The 2-ethoxyethyl m-iodobenzoate thus ob-

tained distils at 147-150° C. (0.8 mm.); yield about 21 g. Viscosity 14.0 cs.

Example 5

2-ethoxyethyl o-iodobenzoate.—A mixture of 57.8 g. of o-iodobenzoyl chloride and 36.7 g. of 2-ethoxyethanol is heated on the steam bath for about one hour. Air is bubbled through the mixture to remove hydrogen chloride and the product is distilled giving a fraction boiling at 112-125° C. (0.07 mm.), about 64 g. Two additional distillations of this fraction gives the pure 2-ethoxyethyl o-iodobenzoate, B. P. 108-110° C. (0.05 mm.).

Additional examples of these new compounds include: 3-methoxypropyl p-iodobenzoate, B. P. 140-142° C. at 0.6 mm.; 3-ethoxypropyl p-iodobenzoate, B. P. 147-150° C. at 0.7 mm.; 2-butoxyethyl p-iodobenzoate, B. P. 149-150° C. at 0.8 mm.; and 2-(beta-ethylbutoxy)-ethyl p-iodobenzoate B. P. 177-180° C. at 1.5 mm. These are prepared by either of the methods used in Examples 1 and 2, using the appropriate starting materials in the same relative molecular quantities.

I claim:

1. A compound having the formula

where Y is an alkylene bridge of from 2 to 5 carbon atoms and at least two carbon atoms separate the carboxyl group from the —OR group, and R is an alkyl group of from 1 to 6 carbon atoms, said compound having a total of from 10 to 18 carbon atoms.

2. A compound having the formula

where R is an alkyl group of 1 to 6 carbon atoms.

3. 2-methoxyethyl m-iodobenzoate having the formula

4. 2-ethoxyethyl p-iodobenzoate, having the formula

5. 2-ethoxyethyl m-iodobenzoate, having the formula

6. 3-ethoxypropyl p-iodobenzoate, having the formula

5

7. 3-methoxypropyl p-iodobenzoate, having the formula

8. A compound having the formula

where R is an alkyl group of 1 to 6 carbon atoms.

SYDNEY ARCHER.
